BOTTLE HOLDER FOR BOTTLE WASHING MACHINES

Filed Sept. 24, 1928

INVENTOR.

John E. Ayers,
BY Louis M. Schmidt.

ATTORNEY.

UNITED STATES PATENT OFFICE.

JOHN E. AYERS, OF HARTFORD, CONNECTICUT.

BOTTLE HOLDER FOR BOTTLE-WASHING MACHINES.

Application filed September 24, 1928. Serial No. 307,954.

My invention relates to improvements in bottle holders for bottle washing machines for use for substantially the same purpose as the bottle holder that is shown and described in the patent issued to myself under date of December 13, 1927, No. 1,652,597, being incorporated in the structure of a conveyor for holding bottles that are to be cleansed in a solution in a tank and by means of jets of cleansing liquid, and the object of my present improvement is to produce a bottle holder that by cooperation with suitable cam tracks or the like is adapted to operate generally positively in gripping and holding the bottle to be operated upon and in releasing the same for being removed from the machine.

In the accompanying drawing:—

Figure 1 is a plan view of a carrier that is equipped with a set of four cups for receiving bottles that are provided with holding mechanism in accordance with my invention, parts of cam tracks for effecting the gripping and the releasing of the bottles being indicated diagrammatically by means of broken lines.

Figure 2 is an elevational view as viewed from one of the lateral ends.

Figure 3 is a similar view on enlarged scale of one of the cups and the adjacent parts as viewed from the direction of the line of travel of the conveyor.

Figure 4 is a sectional view on the line 4—4 of Fig. 1, and showing part of a bottle.

Figure 5 is a plan view showing one of the cups and the holding devices in the position for holding a bottle in pendant position.

My improved bottle holder for bottle washing machines comprises as incorporated in a bottle washing machine a transversely elongated carrier body or carriage that is connected by its ends 11 to a conveyor structure of duplex form so as to be moved in parallelism with a vertical plane, and which body 10, as shown, is provided with a set of four cups 12 for receiving the bottles 13.

The conveyor, as is common, comprises an upper horizontal reach that is relatively free and accessible and a lower horizontal reach that travels in a tank that contains a cleansing solution.

The cups are charged with the bottles while traveling along the latter part of the upper horizontal reach while the conveyor is in motion, some time before reach-

ing the end for the downward drop, and are removed at about the middle of said reach.

When in the charging position the cups 12 are free and open. During the travel along the lower horizontal reach the gripping devices cooperate with the cups for holding the bottles in the pendant position.

The holding or gripping mechanism involves moving parts that are operated by suitable cams. In the present instance such movement is transverse relatively to the line of travel and the cams are indicated diagrammatically in Fig. 1 by the cam 14 at the right and the cam 15 at the left, the moving part being provided with suitable cooperating rolls 16.

The conveyor moves the carrier upwardly as indicated in the drawing by the arrow 17, and the moving part is moved to and fro laterally.

The cams are of track form and comprise each an inclined part or approach part that serves to effect a gradual shifting of the moving part and a longitudinal part, in parallelism with the line of travel of the conveyor that corresponds in position to the full lateral movement of the moving part.

Thus the right cam roll 16 is initially at the full position to the right; the cups 12 are free and open for being charged with the bottles; the carrier moves forward continuously; the cam roll is brought into registration with the inwardly inclined cam part 18 and pushed towards the left; and finally the cam travels along the longitudinal part 19 of the cam 14, which corresponds to the fully closed position for locking the bottles.

The release of the bottle gripping mechanism is effected by the cam 15 in cooperation with the left contact roll 16, said cam comprising the inclined approach part 20 for graduating the shifting and the longitudinal part 21 which corresponds to the position for the full lateral movement.

Cam tracks and rolls such as briefly referred to are ordinary. The moving part and cooperating devices are believed to be novel.

Said moving part 22 is in the form of a sliding structure that supports the cam rolls 16 by its ends and that slides in ways 23 that are provided in the body or carriage 10. Also, the cups 12 are provided in the slide structure 22 so that as the same is moved back and forth transversely of the line of

travel of the conveyor any bottles that are housed therein are carried bodily therewith.

The cups 12 are generally of conical form and are an approximate fit for the neck portion 24 of the bottle 13. When in the operating position within the cup 12 the butt end face 25 of the bottle may be substantially flush with the end face 26 of the bottle.

Considering details of the bottle 13, just 10 below the end face 26 there is a circumferential recess 27 for the closure holding devices and spaced below the same is a second circumferential recess 28.

This second circumferential recess 28 is 15 utilized for effecting the holding of the bottle 13 by the holding or gripping devices to be described.

The gripping is effected by a pair of gripping members 29 that are mounted on the 20 body 10 and engage with the recess 28 by their opposed gripping edges 30.

Said gripping edges 30 are arranged convergent from the right towards the left and are separated by the bottle receiving space 25 31. Said space 31 at the wider bottle receiving end is adapted to admit the bottle freely and at the small end is too small for the passage of the bottle. Intermediate said ends the edges 30 serve to effect a gripping 30 of the bottle to a greater or less extent, as the case may be. The parts described are constructed and arranged so that at the position of the full movement in the direction for gripping any and all bottles within the 35 range of the machine will be positively held or gripped by the edges 30.

Such gripping, however, involves a relatively tight grip for bottles having a relatively large size for the neck and for the 40 diameter for the recess 28.

In some cases it may be desirable to provide for some yielding of the gripping members or jaws 29. One way of doing this is to make the jaws of relatively heavy sheet 45 metal that is bent to some extent so as to

be operative as a spring under relatively severe stress or strain.

Thus the jaw member 29, as shown, comprises the horizontal part or branch 32 of a sheet metal strip that terminates in the gripping edge 30. In off-set relation to said gripping branch 32 is the supporting branch or part 33 that is in the form of a foot that is secured to the body 10 by means of a pair of screws 34. Intermediate the branches or parts 32 and 33 is the off-setting connecting part 35.

The walls of the cups 12 are provided with slots 36 for admitting the jaw branches 32, which are located so that the gripping edges 60 will register with the bottle recesses 28.

As described, the cups are moved laterally, carrying the bottles therewith so that the edges 30 engage in the recess 28 along the narrower portions of the space 31, for effecting the gripping and for releasing the cups with their loads are moved in the reverse direction.

I claim as my invention:—

In combination in a bottle holder for use 70 in a bottle washing machine, a body for being moved for carrying the bottle to be operated upon, a moving member mounted for sliding on said body and provided with a cup for receiving the neck portion of said bottle, 75 a pair of jaw members fixedly mounted on said body and provided with gripping edges that are opposed and separated by a space for receiving said bottle neck portion, the walls of said cup being slotted for admitting 80 said gripping edges to the bottle neck receiving space of said cup, and said gripping edges serving to define a wedge-shaped space so that the separating space between the edges that are in registration with said bottle 85 neck receiving space will change as the relative position of the cup and jaw members is changed.

JOHN E. AYERS.
